UNITED STATES PATENT OFFICE.

JOHN DOLMAN, OF NUNEATON, ENGLAND, ASSIGNOR TO A. W. PHILLIPS, LIMITED, OF NUNEATON, ENGLAND, A COMPANY OF GREAT BRITAIN.

DESIGN FOR A COVER PIECE FOR LAWN-TENNIS BALLS.

Application filed October 12, 1925, Serial No. 15,099, and in Great Britain July 2, 1925. Term of patent 7 years.

To all whom it may concern:

Be it known that I, JOHN DOLMAN, a subject of the King of Great Britain, residing at Albion Works, Nuneaton, in the county of Warwick, England, have invented a new, original, and ornamental Design for a Cover Piece for Lawn-Tennis Balls, of which the following is a specification, reference being had to the accompanying drawing, forming part thereof.

I claim—

The ornamental design for a cover piece for lawn tennis balls as shown and described.

JOHN DOLMAN.
